No. 84,371.

PATENTED NOV. 24, 1868.

F. OGDEN.
ROTARY STEAM ENGINE.

FERRIS OGDEN, OF MEADVILLE, PENNSYLVANIA.

Letters Patent No. 84,371, dated November 24, 1868.

IMPROVEMENT IN ROTARY STEAM-ENGINES.

The Schedule referred to in these Letters Patent and making part of the same.

To all whom it may concern:

Be it known that I, FERRIS OGDEN, of the city of Meadville, in the county of Crawford, State of Pennsylvania, have invented a new and improved Rotary Steam-Engine; and I do hereby declare that the following is a full and exact description of the same, reference being had to the accompanying drawings, and the letters of reference marked thereon.

Figure 1 is an end view of my engine, with one side thereof removed to better show the internal construction of the same.

Figure 2 is a perspective view of the same, showing an external view of the engine with all its parts adjusted in working order.

A A are the two halves, each having a recess, B, one inch, more or less, turned in its inside face, which recesses form, when the two halves A A are secured together, the "steam-space" or cylinder, through which the piston C travels in its revolutions.

The parts A A also form the "ejection and induction-steam ports" b b', and a seat for the "plug-valve" or abutment D, which is fitted in with a taper, and held in place by a set-screw, shown in the blind lines at d, enabling the operator to set the abutment D farther in, making it tight, when so worn as to allow the steam to escape.

The abutment D has a cavity in the side, and revolves once at every revolution of the piston C, in such a manner as to allow the latter to pass under, and then immediately closing down behind it, shutting off communication with the exhaust-port b'.

The extended portion l l' of the piston C is shown parted in the drawing, and put together with tenons, and fastened together by rivets; the tenons having "loss motion" in the rivet-holes, and spiral or other springs behind them, in order to pack themselves against the abutment, as at l', allowing steam to be let on when the parts C and D reach the position shown in fig. 1, and continuing thus until just before the packing n of the piston reaches the exhaust-port b', when it is shut off by the valve G.

Power is transmitted to the main shaft E by the arm J, which passes, through a hole in the ring m, up into the piston.

The space through which the arm J passes in revolving is closed by the ring m, the latter being supported by a short flange projecting from each of the halves A A, and revolving with the arm J.

The ring m has "a bearing" with the abutment D, and the two roll together.

The piston is packed on the top, n, and the two ends with steam packing.

The main shaft E is supported by pillar-blocks F F, and is connected with the valves D and G, by means of the upright shaft H and the bevel-gear wheels a a', c c', and e e'.

The steam-chest I, within which the "cut-off" valve is seated, has exhaust-ports f f'. At the top these ex-

haust-ports unite in one exhaust-pipe. By this construction the ports b and b' are alternately opened and closed as the reverse valve K is placed in different positions.

Through the bottom of the steam-chest I there is a groove with its sides parallel, and the bottom of the groove parallel with the sides of the thimble h, and into this groove is fitted the piece g, steam-tight.

The thimble h is cut away, as shown in fig. 3, between the ends, which are connected by the piece h'. Up into this thimble extends the piece g, which forms a steam-joint at the ends with the thimble h, and also against the plug-valve G. The piece g, the thimble h, and the valve G, are pushed in until they are tight, and are kept in place by a pressure of steam on their large ends.

The steam enters by the steam-pipe j, (see fig. 2,) into the centre of the valve G, and passes through the slot i, (see fig. 4,) in the side, and also, through k and b, into the cylinder between the abutment D and the piston C, forcing the latter around in the direction of the arrow.

The piece g, thimble h, and plug G form a variable cut-off valve.

In the position shown in fig. 1, the engine takes steam through about five-sixths of its revolution, or until the slot i, revolved by the gear c c', passes around in the direction of its arrow, and is closed by the port h of the thimble.

If the thimble h is turned by the lever M, segmental gear L, and pinion S, in the direction of its arrow, steam is shut off sooner, and thereby the steam may be graduated.

Thus if the lever M is moved until the pin p comes into the hole q on the quadrant, the engine takes steam through one-half its revolution. If the pin p is moved to r, it takes steam through one-quarter, &c., and allows the steam to expand through the remainder of the revolution.

The reverse valve K has two openings, O O', which will cover one of the ports, f f', and one of the ports, k and k', at the same time. (See fig. 1.) As shown in the drawing, h is brought into communication with b, and f' with b'. If the slide-valve K is moved to the right by the lever N, and the arm O connected by a journal, T, the exhaust f will be brought into communication with b, and k with k', letting in the steam on the opposite side of the abutment D, reversing the motion of the engine.

When the valve K leaks from wear, the steam-chest I set down with the screws t t.

If the valve K is so moved that the pin in the lever N comes into the middle hole in the quadrant P, the ports h and k' will both be closed, thus making a throttle of the valve K.

The halves A A are both fastened to the bed-plate Q by a key, U, through the bottom of their flanges.

The shape of the halves and the ring m overcomes

all lateral pressure on the shaft E. This is the object of their construction.

The engine is connected with other machinery by the fly-wheel R.

What I claim as my invention, and desire to secure by Letters Patent, is as follows, to wit:

1. I claim the two halves A A, the ring m, the arm j, and the piston C, constructed as described.
2. I claim the abutment D, constructed as described.

3. I claim the thimble h and the plug-valve G, constructed as described.

4. I claim the steam-chest I, constructed as described.

5. I claim the arrangement of the parts designated in the foregoing clauses of the claims, constructed as described.
